INVENTOR
Rebekah E. Raney
BY
M. C. Frank
ATTORNEY

UNITED STATES PATENT OFFICE.

REBEKAH E. RANEY, OF SAN FRANCISCO, CALIFORNIA.

HOSE GUARD.

Application filed December 24, 1923. Serial No. 682,518.

To all whom it may concern:

Be it known that I, REBEKAH E. RANEY, a citizen of the United States, residing at San Francisco, in the county of San Francisco and State of California, have invented certain new and useful Improvements in Hose Guards, of which the following is a specification.

My invention relates to improvements in guards, for the protection of the hose during the operation of cleaning and polishing the shoes, and is constructed in such a manner that it effectively covers the hose of the wearer about his shoe top, and prevents the hose from being soiled or stained by the bootblack during such operation.

The invention is especially designed for use in connection with low shoes, such as oxfords or pumps.

As a general rule, bootblacks are more or less careless in the application of the cleaning fluid and polish to the shoes, and it is an annoying experience to have the hose daubed or soiled above the shoe tops, and especially so if the hose is of light color or white, so extensively worn at present, and the principal object of this invention is the production of a guard to anticipate and to prevent such an annoyance.

Another object of the invention is to construct a guard adapted to cover the hose above the shoe top, and to overlap the outside of the top edge of the shoe to prevent any misapplication of the cleaner or polish on the hose.

Another object is to construct a guard of very cheap material, such as paper, and which is designed to be used but once and then discarded.

Another object is to provide the guard with tongues which slip into the shoe at each side thereof, and in the case of slippers with an additional tongue at the front, to position the guard on the edge of the shoe. The overlapping portion in combination with the tongues serve to limit and support the guard on the edge of the shoe, and prevent downward slippage of the same in the shoe.

Another object is to construct a guard having positive fastening means to hold the same snugly about the ankle, and which may be readily adjusted, released, or torn away.

A further object is to provide the guard with a frontal extension for slippers, and for the type of low shoe having one or more

cross-straps. The said extension being adapted to cover the straps and the foot instep, and tongue thereof to slip in the toe, with its adjacent edges overlapping the outside edge of the shoe.

A still further object is to provide a guard with an end extension, to cover and hold under cover the bows and free ends of the shoelace during the polishing operation.

And another object is, in some cases, to serrate the shoe-top overlapping portion of the guard for character effects in dressing the shoe, that is, parts under the serrations will appear dulled compared to the polished shoe when the guard is removed.

I attain the above objects by the novel construction of my guard, and other objects and advantages of the invention will appear in the subjoined description of the accompanying sheet of drawings, in which:

Figure 1 is a perspective view of a low shoe, such as an oxford, showing my guard in place with its depending tongues in the shoe. The guard is held about the ankle of the wearer by the adhesive end margin thereof.

Fig. 2 is a perspective view of another form of low shoe, such as a slipper, showing my guard provided with a frontal extension to cover the instep of the wearer, and having a tongue at the lower end thereof for engagement within the toe of the shoe.

Fig. 3 is a perspective view of the guard shown in Fig. 1 removed from the shoe, showing the retaining tongues extending therefrom.

Fig. 4 is a perspective view of the guard shown in Fig. 2, illustrating the general shape of the guard and frontal extension and tongue thereof.

Fig. 5 is a perspective view of a guard similar to Fig. 1, except that one end thereof is made longer and is provided with an additional adhesive layer, so that the said end may be folded back to inclose and hold the loose ends of the shoe lace away from the shoe.

Fig. 6 is an expanded view of the guard of Fig. 1, showing the tongues and adhesive layer, and in addition a serrated lower edge to form a character design about the upper part of the shoe during the polishing thereof.

Fig. 7 is an expanded view of the guard of Fig. 2, showing the frontal extension

and string fastener. Part of the frontal extension is torn away.

Adverting to the drawing and figures thereof; the number 10 designates the body 5 of my guard, and which is preferably of a rather light, stiff and pliable paper, cut in the form of a strip having irregular top and bottom edges 11 and 12 respectively, and outer ends 13 and 14. The strip is so 10 shaped that when the ends are brought together and overlapped as shown in Figs. 1, 2, 3, 4 and 5, the upper edge 11 forms an ankle-fitting ellipse and the lower edge 12 a shoe-fitting ellipse, and when drawn together as shown in Figs. 1 and 2 form a snug fit about the ankle and upper edge of the shoe.

The depending tongues 15 and 16 are formed as part of the lower edge 12 of the 20 guard body, and are cut partly into the body as indicated at 17, and when applied are bent inwardly and slipped into the shoe, thereby allowing the lower edge 12 to overlap the upper edge of the shoe top 18, which 25 overlapping edge extends entirely around the shoe except where the tongues extend inwardly therefrom at opposite sides of the shoe.

Referring to the type of guard shown in 30 Figs. 2, 4 and 7, it will be noted that I have provided it with a frontal extension 19, which is a continuation of the guard body, and is adapted to be applied over the strap and buckle 20 of a slipper or pump 21. A 35 tongue 22 is provided at the lower end of said extension for slipping the same in the toe of the shoe as shown in Fig. 2. Said frontal extension covers the otherwise exposed portion of the hose between the strap 40 and toe and effectively prevents the soilure of the hose thereunder, and helps to retain the guard in proper position in conjunction with the adjacent overlapping edges outside the shoe top as shown at 23.

45 The lower edge 12 of the guard may be serrated with any chosen cut as indicated at 24, to form a character design about the upper part of the shoe during the polishing thereof. This character design feature is 50 much desired in some types of women's shoes.

The retaining of the guard about the ankle is preferably accomplished by a narrow strip of gum or adhesive 25, applied 55 along the inner edge of the end 14 of the guard, or by a fastener 26 and string 27 as commonly employed on large envelopes and as shown in Figs. 2 and 7.

In Fig. 5, I have shown an end made 30 longer and which may have applied thereto two strips of adhesive 28 and 29; the strip 28 when moistened retaining the drawn guard in place about the ankle, and the strip 29 maintaining the end in place when 35 folded back upon itself to inclose therebe-

tween the bows or loose ends of the shoe lace.

In operation, the bootblack will determine the guard for the shoe he is about to shine, or one may call for a character design guard, and fold it about the ankle in the manner previously explained, and when drawn snugly to position he will moisten the gummed edge thereon and seal the flap. If a stringed type guard is employed he 75 will draw the string 27 tightly and wind the free end around the eyelet-held disc 30 suitably positioned on the guard.

Having thus illustrated and described my invention, the patent protection that I desire, is all of that which comes within the spirit and scope of the invention as claimed.

I claim:

1. A hose guard, comprising a strip of flexible material cut to encircle the ankle 85 above the shoe top, and having tongues extending from the lower edge thereof adapted to slip within the shoe, and the remaining lower edge adapted to overlap the entire outside upper edge of the shoe, the said edge 90 of the latter supporting the guard on the shoe.

2. A hose guard, comprising a strip of flexible material adapted to encircle the 95 ankle and having tongues extending from the lower edge thereof adapted to slip within the shoe, the remaining lower edge thereof adapted to extend outside and below the upper edge of the shoe, the ends of said strip adapted to overlap, and one end extended to fold back upon itself to inclose the bows of the shoelace, and means provided for holding the said ends in overlapping relation.

3. A hose guard, comprising a flexible strip of material shaped to encircle the ankle above the shoe, the lower edge thereof having projecting tongues adapted to slip within the shoe at opposite sides and having a frontal extension as a continuation of the 110 guard and provided with a tongue, the said extension adapted to extend over the instep of the foot and the tongue into the toe of said shoe.

4. As an article of manufacture, a hose 115 guard of the character described adapted to be used but once, consisting of a strip of paper shaped to encircle the ankle and the lower edge thereof to encircle the top outside margin of the shoe, and part of said edge adapted to engage the inside margin of the shoe, whereby the top edge of the shoe supports the device thereon, and adhesive means carried by said strip of paper 120 for retaining the guard in position about the ankle.

In testimony whereof I affix my signature.

REBEKAH E. RANEY.
